RUDOLPH BECKER, OF ROSELLE PARK, NEW JERSEY, ASSIGNOR TO THE SINGER MANUFACTURING COMPANY, A CORPORATION OF NEW JERSEY.

GUIDE FOR STRAW-BRAID-SEWING MACHINES.

1,290,052.

Specification of Letters Patent.

Patented Jan. 7, 1919.

Application filed February 27, 1917. Serial No. 151,187.

To all whom it may concern:

Be it known that I, RUDOLPH BECKER, a citizen of the United States, residing at Roselle Park, in the county of Union and State 5 of New Jersey, have invented certain new and useful Improvements in Guides for Straw-Braid-Sewing Machines, of which the following is a specification, reference being had therein to the accompanying drawings.

10 This invention relates to straw-braid sewing machines making a chain-stitch and including hooked and eyed needles operatively arranged below the throat-plate. It is especially concerned with edge-guiding means 15 for use in connection with this type of machine.

In the manufacture of straw-hats it is common to fashion the hat-body, including the crown and a part of the brim, separately 20 from the brim and then to stitch them together. The brim is usually made of a plurality of layers of material. By this method of manufacture it is possible to conceal from view most of the thread, leaving visible only 25 loops of thread as long as the distance between needles. In uniting the edge-portions of the hat-body and brim it is desirable to conceal the long thread-loops between successive needle-punctures.

30 This invention aims to provide new and improved edge-guiding means for bending the under of the layers of a brim to one side during the stitching operation after which the under layers may be bent back glued and 35 ironed flat thus effectively concealing the major portion of the thread.

The construction preferably comprises a rack movable lengthwise by a pinion and carrying a pair of relatively adjustable edge- 40 guides whose active material engaging portions are located in advance of the needles and above the throat-plate which is undercut in such a way as to form a warped surface that deflects the under of superimposed plies of braid from a flat condition 45 transverse to a bent condition to one side of the line of stitch-formation. One of the edge-guides, preferably the upper, carries a separating lip and is made adjustable relatively to the other edge-guide so as to permit the edges of the braid being arranged out of alinement if desired as when it is wished to make what is known as a "corded" edge.

The invention also consists in certain de-

tails of construction which will appear in 55 the following description of the device shown in the accompanying drawings, in which Figure 1 is a side elevation of the attachment in use, the work being indicated in section. Figs. 2 and 3 are a plan and an end 60 elevation respectively, of the attachment and Fig. 4 is a cross-section on the line 4—4, Fig. 2.

The invention is embodied in a chain-stitch machine employing a pair of upwardly directed needles N for passing the thread through the material. The needles are supported and actuated from beneath the throat-plate 1 of the machine through the feed-dog slot 1' by any suitable means 70 such as shown in patent to Jasper, No. 857,070, issued June 18, 1907.

The throat-plate 1 is secured to the end-cap 2 within a recess 3 by screws 4, being formed in any suitable manner to provide an 75 undercut portion defining a warped surface comprising a forward separating part 5 and a deflecting and bending part 6, located in advance of the needles, and a holding-vertical part 7, located at one side of and 80 extending rearwardly beyond the needles.

Above the throat-plate 1 in advance of the needles N a pair of edge-guides 8 and 9 are arranged. One of the guides, preferably 9, has a lip 10 for separating the hat-body 11 85 from the hat-brim 12, as clearly shown in Fig. 1, so that an intermediate layer of the braid 13 regardless of its thickness will abut against the lower guide 8 in making a "corded" edge, i. e., an edge having an intermediate layer 13 projecting from between the layers 11 and 12 of the hat-brim, as shown in Fig. 1.

The lip 10 also serves to restrain curling of the intermediate layer 13. The edge-guides 8 and 9 are bent as shown in the drawings and are relatively adjustable, a slot 8' being provided for this purpose in the horizontal arm 8'' of the lower guide to receive the screws 9' tapped into the horizontal arm 9'' of the upper guide. The lower guide 8, preferably but obviously not necessarily, is pivoted on the stud-screw 14, tapped into the lug 15 extending upwardly from a slide-plate 16 held frictionally in place on a fixed 100 rib 17 by a spring-washer 18 and a screw 19 tapped into the rib. The slide-plate 16 is equipped with a rack 20 whose teeth mesh

with those on a pinion 21. A milled-head 22 affords convenient means for turning the pinion and sliding the plate 16 on the rib 17.

The edge-guides 8 and 9 are arranged in advance of the needles N and presser-foot 23, the upper guide 9 being beveled, as indicated at 24, to permit the lip 10 being extended close to the up-turned toe 25 of the presser-foot in order that the upper layer of braid 11 may be smoothed out before it reaches the stitching point.

It will be apparent that the construction described affords simple and compact means for concealing the stitches. The edge-guides 15 are laterally adjustable for several purposes.

The guides may be used for making straight or "corded" edges, for varying the position of the line of stitching relative to the edge of the brim, and also may be thrown out of 20 effective operative position by swinging them upwardly on the pivot 14 in order to clear the end-cap of obstructions in the general stitching operations for which a machine is largely used.

While broadly from certain aspects the construction embodying the invention is applicable to machines having a needle or needles directed downwardly, *i. e.*, supported and actuated from above the throat-plate, it is to be noted that it is especially 30 advantageous in machines having a needle or needles directed upwardly, *i. e.*, supported to act from below the throat-plate, the advantage consisting in the closeness with 35 which the vertical holding portion 7 of the warped surface below the throat-plate may be located to the needles as clearly evidenced by an inspection of Figs. 1 and 2.

Having thus set forth the nature of the 40 invention what I claim herein is:—

1. In a guide for sewing machines having stitch-forming mechanism including a needle, a throat-plate having a curved undercut portion in advance of the needle for deflecting material from a position transverse to a position to one side of the line of stitching and an edge-guide located above the throat-plate.

2. In a guide for sewing machines, having 50 stitch-forming mechanism including a needle, a throat-plate having a curved undercut portion in advance of the needle for deflecting material from a position transverse to a position to one side of the line of stitching.

3. In a guide for straw-braid sewing machines having stitch-forming mechanism including coöperating upwardly directed hooked and eyed needles, a throat-plate having a curved undercut portion and a dividing lip in advance of the needles to deflect a layer of material from a flat condition transverse to a bent condition at one side of the line of stitching, and an edge-guide located 60 above the throat-plate.

4. In a guide for straw-braid sewing machines, a throat-plate, stitch-forming mechanism including a pair of needles operatively arranged below the throat-plate, said throat-plate being undercut in advance of the needles to deflect a layer of material from a flat condition transverse to a bent condition at one side of the line of stitching, and an adjustable edge-guide located above the throat-plate in advance of the needles. 70

5. In a guide for straw-braid sewing machines having stitch-forming mechanism including a needle, a throat-plate undercut in advance of the needle to deflect a layer of material from a flat condition transverse to a bent condition at one side of the line of stitching, and a pair of relatively adjustable and superimposed edge-guides located above the throat-plate in advance of the needle. 75

6. In a guide for straw-braid sewing machines having stitch-forming mechanism including a needle, a throat-plate undercut in advance of the needles to deflect a layer of material from a flat condition transverse to a bent condition at one side of the line of stitching, and edge-guiding and separating means located in advance of the needle and above the throat-plate. 80

7. In a guide for straw-braid sewing machines having stitch-forming mechanism including a needle, a throat-plate undercut in advance of the needle to deflect a layer of material from a flat condition transverse to a bent condition at one side of the line of stitching, a pair of edge-guides located above the throat-plate in advance of the needle, and a material separating lip carried by one of the said guides in spaced relation with the throat-plate. 95

8. In a guide for straw-braid sewing machines having stitch-forming mechanism including a needle, a throat-plate undercut in advance of the needles to deflect a layer of material from a flat condition transverse to a bent condition at one side of the line of stitching, a pair of relatively adjustable edge-guides located above the throat-plate in advance of the needle, a material separating lip, carried by one of said edge-guides, and means for simultaneously adjusting both guides toward or away from the line of stitching. 100

9. In a guide for straw-braid sewing machines having stitch-forming mechanism including a needle, a throat-plate undercut in advance of the needle to deflect a layer of material from a flat condition transverse to a bent condition at one side of the line of stitching, a pair of relatively adjustable edge-guides, a material separating lip on one of said edge-guides, means for permitting both guides being thrown to an effective or ineffective position without alteration of their relative arrangement. 115

10. In a guide for straw-braid sewing ma- 120

chines having stitch-forming mechanism including a needle, a throat-plate undercut in advance of the needle to deflect a layer of material from a flat condition transverse to 5 a bent condition at one side of the line of stitching, edge-guiding and separating means located above the throat-plate in advance of the needle, a pivotal support for said means, whereby they may be thrown out 10 of the way, and a rack-and-pinion for adjusting said means toward and from the line of stitching.

11. In a guide for straw-braid sewing machines having stitch-forming mechanism including a needle, a throat-plate undercut to define a warped surface comprising a separating part, a bending and deflecting part, and a holding-vertical part whereby the 15 under of superimposed layers of material 20 may be separated from the upper layer and deflected to one side of the needle as it passes the stitching point.

12. In a guide for straw-braid sewing machines having stitch-forming mechanism including a needle, a throat-plate undercut to define a warped surface comprising a separating part and a bending and deflecting part located in advance of the needle, and a holding-vertical part located at one side of 25 30 the needle.

13. In a guide for straw-braid sewing machines having stitch-forming mechanism including coöperating upwardly directed hooked and eyed needles, a throat-plate having a curved cut away portion beneath the 35

material supporting portion to lead the under of superimposed plies of material past the needles entirely to one side thereof.

14. In a guide for sewing machines having stitch forming mechanism including a 40 needle, a presser-foot having an up-turned toe, a throat-plate having an undercut portion for leading the under of two superimposed plies of material laterally past the needle, an edge-guide for the upper of said 45 superimposed plies of material, a second edge-guide for a third ply of material, a lip carried by one of said edge-guides and co-operating with the up-turned toe of said presser-foot to smooth said third layer of 50 material before it reaches the needle.

15. In a guide for sewing machines having stitch forming mechanism including a needle, a throat-plate having a horizontal dividing lip and an under, curved deflecting 55 portion in advance of the needle, and a vertical guiding portion at one side of the needle, whereby layers of material may be divided and the lower one deflected from a position transverse to the line of stitching to 60 a point at one side thereof.

16. In a guide for sewing machines having stitch-forming mechanism including a needle, a throat-plate having a dividing lip in advance of the needle and an undercut deflecting portion curving to a point at one 65 side of the needle.

In testimony whereof I have signed my name to this specification.

RUDOLPH BECKER.
